UNITED STATES PATENT OFFICE.

JOHN L. WHEELER, OF PITTSBURG, CALIFORNIA.

SANITARY TOILET-SEAT ATTACHMENT.

Application filed May 1, 1923. Serial No. 635,838.

To all whom it may concern:

Be it known that I, JOHN L. WHEELER, a citizen of the United States, residing in the city of Pittsburg, county of Contra Costa, and State of California, have invented a new and useful Improvement in a Sanitary Toilet-Seat Attachment, of which the following is a specification.

My invention relates to improvements in sanitary toilet seats wherein an apertured paper web is provided with regular spaced apertures arranged to be successively registered with the seat aperture.

The primary object of the present invention is to provide a new and improved sanitary toilet seat cover or attachment by means of which a new sanitary cover may be provided with each successive use of the seat.

Another object of the present invention is to provide a new and improved device of the character described that shall be simple, inexpensive and practicable, and easily operated to move an apertured paper web, having regularly spaced apertures therein, to cause successive apertures in said web to register with the seat aperture.

A further object of the invention is to provide improved means for moving manually the paper web in either direction whereby the paper web may be reversed when an aperture has passed the seat aperture whereby said apertures in the seat may be properly registered with the seat aperture.

A still further object is to provide an improved means for engaging and disengaging the paper web moving means to facilitate removal or renewal of the paper web and the operation of the same.

I accomplish these and other objects by means of the device disclosed in the drawings forming a part of the present specification wherein like characters of reference are used to designate similar parts throughout the said specification and drawings, and in which—

Fig. 1 is a front elevation, partly broken, disclosing the application of my improvement to a toilet seat;

Fig. 2 is a plan view thereof;

Fig. 3 is an enlarged longitudinal sectional view of one of the rotating elements disclosing the means for gripping the paper moving means, the parts being dis-

closed in an inoperative or disengaging position;

Fig. 4 is a similar view but disclosing the gripping elements in an operative or engaging position;

Fig. 5 is a transverse sectional view of the device as disclosed in Fig. 3;

Fig. 6 is a similar view disclosing the elements as in Fig. 4;

Fig. 7 is a broken detailed view of one of the bearing rods removed from its respective roller;

Fig. 8 is a broken detailed view of one of the devices for locking the bearing rods within the bracket; and

Fig. 9 is a vertical sectional view taken on line 9—9 of Fig. 8 in the direction indicated.

Referring to the drawings the numeral 1 is used to designate a toilet seat of the square type, which is so shaped for the purpose of facilitating the passage of a paper web 2 over the side edges 3 of said seat 1.

Mounted upon each side of the seat 1 is a bracket 3 arranged to rotatably support 80 what I term a bearing rod 4 upon which is mounted a roller having a plurality of radially disposed slots 6 therein. A sleeve 7 is loosely mounted upon each roller 5 and the opposite of the paper web 2 is detachably connected to opposite sleeves 7 in any suitable manner, which, forming no portion of the present invention, is not illustrated.

The paper web is provided with regularly spaced apertures 8 arranged to register with the seat aperture, said web being moved to register successive apertures and may be operated from either end in order that the direction of the movement of the web may be reversed in order to properly register the apertures when one of the apertures in this paper web is inadvertently moved too far or past the seat aperture.

Mounted within each of radial slots of each roller 5 is a gripping element, formed 100 preferably of annular washers 9 loosely held in place by means of an annular keeper 11 mounted within an annular groove 12 on the roller 5 and intersecting the radial slots. The radial slots 6 are 105 preferably formed at right angles to each with a set of radial slots adjacent each end of the roller 5.

The bearing rod 4 is slidably mounted within the roller 5 and projects beyond 110

both ends thereof, one end, the outer or farthest one, being reduced in diameter and made round so as to engage a suitable aperture within one of the brackets to 5 rotatably support that end of said rod 4 and its respective roller 5, while the opposite end of the said bearing rod 4 is provided with a suitable washer 16 and a rigidly secured thumb nut 17.

- 10 The washer 16 is arranged to be rotatably mounted within a circular aperture 18 within a plate 19 mounted upon the front or near end of the bracket 3 and is normally held in position by means of a member 21 slidably mounted upon the plate 19 as at 22 and having a lateral extension 23 by means of which said slide or member 21 may be operated to retain or release the washer 16 for the purpose of rotatably 20 retaining or removing the bearing rod 4, in the latter case as when removing the rollers 5 to renew the paper web.

Suitable covers 26 are hingedly secured as at 27 to the brackets 3 whereby the rolled 25 paper web 2 may be protected from contact.

The paper web 2 will be provided already wound by the manufacturer upon one of the cardboard sleeves 7, the inner or wound 30 end of said web 2 being detachably connected to the said sleeve 7 in any suitable manner.

This sleeve 7 with its wound web 2 is first placed upon the roller 5, the rod 4 having been withdrawn, and placed between the brackets 2 on either side of the seat 1. The rod 4 is then inserted through the bearing brackets 3 until the wedge portions 14 thereof engage and project or actuate the gripping elements 9 to engage the internal 40 surface of the sleeve 7 whereby said sleeve 7 may be rotated with the roller, in a manner hereinafter more fully described. In order to limit the movement of the bearing rod 4 within the roller 5 I have provided a transversely arranged pin 28 within said roller 5 which is slidably engaged by a slot 29, said slot being of substantially the same length as the wedge portions 14 of 45 said rod 4, by means of which arrangement a longitudinal movement of said rod 4 within the roller 5 is permitted to engage and disengage the gripping elements 9.

When the rod 4 is moved inwardly to actuate the gripping elements 9 and thereby rigidly connect the sleeve 7 with the roller 5, the sliding member 22 is moved downwardly by means of the lateral extension 23 to cover partially the washer 17 and thereby rotatably lock the said bearing rod 4 in an operative position within the brackets 3.

The web 2 is now threaded over the seat 1 and the free end of said web detachably 55 connected in any suitable manner to the op-

posite sleeve 7 which has been mounted upon its bearing rod 4 in a manner hereinbefore described.

By means of the thumb nut 17 the roller 5 and its sleeve 7 is now rotated until one 70 of the apertures 8 in the paper web 2 registers with the seat aperture. Should the aperture in the web be inadvertently or otherwise moved past the seat aperture the web may be reversed by rotating the opposite thumb nut 17 until said aperture registers with the seat aperture.

Having thus described my invention what I claim as new and desire to secure by Letters Patent—

1. In a sanitary attachment for toilet seats, a roller detachably mounted upon each side of a toilet seat; a sleeve mounted upon each roller to receive a paper web detachably connected to each roller and passing 80 over the seat and having apertures therein arranged to register with the seat aperture; and expanding and contracting mechanism mounted within each roller and arranged to expand and contract to engage the sleeve 90 thereon and to rotate said sleeves in either direction when engaged, whereby apertures in the paper web may be moved to register with the seat aperture.

2. In a sanitary toilet seat attachment a 95 roller detachably mounted upon each side of said seat and provided with longitudinal slots; a sleeve mounted upon each roller to receive a sanitary paper web connected 100 between said rollers and passing over the toilet seat and having spaced apertures therein arranged to register with the toilet seat aperture; gripping elements mounted within the slots in the rollers and arranged to be projected to engage the sleeve and to be recessed to disengage the same; and roller rotating means mounted within each roller and arranged to project said gripping elements to engage the sleeve whereby said sleeve may be rotated to move the paper web and 110 thereby register successive apertures in said web with the toilet seat aperture.

3. In a sanitary seat attachment, a suitable bracket mounted upon each side of said seat; a roller detachably mounted for rotation in either direction within each bracket; a sleeve detachably mounted upon each roller to receive a paper web mounted between the rollers and passing over the toilet seat and having apertures spaced at regular intervals and arranged to register with the seat aperture; gripping elements mounted within each roller and arranged to grip the sleeve thereon; and rotating means detachably connected to and arranged to rotate the rollers and sleeves in either direction whereby the apertures within the paper web may be registered with the seat aperture, said rotating means being arranged to actuate the gripping elements to engage the 130

sleeves and to actuate said elements to disengage said sleeves.

4. In a sanitary toilet seat attachment, a bracket mounted upon each side of said seat; a bearing rod mounted within each bracket; a roller slidably mounted upon each rod and having radial slots therein; a sleeve mounted upon each roller to receive a paper web mounted between the sleeves and passing over the toilet seat and having apertures therein arranged to register with the seat aperture; and gripping

elements mounted within the longitudinal slots of the rollers and arranged to be actuated by the bearing rods to engage and disengage the sleeves whereby the paper web may be moved in either direction by rotation of said rods to register the apertures in the paper web with the aperture in the seat.

In witness whereof I hereunto set my signature.

JOHN L. WHEELER.
